LUBRICATING DEVICE

Andrew C. Danver and Samuel R. Danver,
Pawtucket, R. I.

Application July 6, 1931, Serial No. 548,808

20 Claims. (Cl. 123—196)

This invention relates to apparatus for handling fluids, and more particularly to a device for supplying liquid lubricant to internal combustion motors or engines.

One object of the invention is to provide a device for lubricating internal combustion engines which is operative when the engine is at rest to segregate a measured quantity of lubricant for lubricating the motor in starting; and normally to continuously provide the proper amount of lubricant when the engine is running.

Another object of the invention is to provide a device for lubricating internal combustion engines which will be continuously operative without adjustment to store lubricant when the engine is at rest and to supply the lubricant at various rates of flow in accordance with the speed of the engine when running.

Another object of the invention is to provide a device of the type specified which will not alter or affect the proper carburetion of the fuel.

Another object of the invention is to provide a device of the type specified for introducing a heat-resisting and decarbonizing lubricant directly into the cylinders of an internal combustion engine whereby, in addition to lubricating the bearings, it will decompose the carbon formed by previous combustion and deposited on the pistons and other parts.

Another object of the invention is to provide a device of the type specified which is simple and compact in construction and reliable and efficient in operation.

Further objects of the invention are set forth in the following specification which describes a preferred form of construction of the invention, by way of example, as illustrated in the accompanying drawings. In the drawings:

Fig. 1 is a side elevation of the device shown as connected to the intake manifold of an internal combustion engine;

Fig. 2 is an end elevation of the device as viewed from the left in Fig. 1;

Fig. 3 is a plan view of the same;

Fig. 4 is a vertical sectional view of the device taken on line 4—4 of Fig. 3;

Fig. 5 is a horizontal sectional view of the same taken on line 5—5 of Fig. 4; and

Fig. 6 is a bottom plan view of the device.

Referring to the drawings, wherein like parts are indicated by the same reference numerals, a lubricating system constituting one embodiment of the invention includes a lubricant reservoir 10 which may be connected to the intake

manifold 11 of any conventional form of internal combustion motor or engine. The apparatus is adapted to be mounted upon the side of the motor cylinder block, the dash of an automobile or any other suitable support, by means of a bracket 12 having a horizontal shelf portion 13 which may constitute the top or cover of the reservoir 10. The reservoir 10 is provided with a horizontal circular bottom-plate 14 corresponding to the top-plate 13. Held between the top-plate 13 and bottom-plate 14 is a cylindrical casing or shell 20, preferably of glass, which forms the main reservoir chamber. The ends of the cylinder 20 are fitted to grooves 15 and 16 in the plates 13 and 14, with annular gaskets 17 and 18 positioned in the grooves to provide air- and fluid-tight joints. The cylinder 20 is clamped in place between the plates 13 and 14 by means of bolts 21 passing therebetween. Each bolt is provided with a slotted head 22 and a washer 23 thereunder at one end, the other end being externally threaded at 24. The bolts 21 are passed through vertically aligned apertures 25 and 26 in the upper and lower plates 13 and 14 of the reservoir, the apertures 26 in the bottom-plate being internally threaded to receive the threaded extremities of the bolts.

The top-plate 13 is provided with an axial threaded aperture 27 for use in filling the reservoir, the aperture being normally closed by a threaded cap 28 which is provided with a breather hole 29, see Fig. 3. Forward of the central aperture 27 a threaded aperture 30 is formed in the top-plate 13 and axially aligned therewith is a threaded aperture 31 in the bottom-plate 14. An outlet plug 32 provided with a reduced externally threaded portion 33 is screwed into the threaded aperture 31 in the bottom-plate 14 to be tightly seated therein.

An axial passage 34 is formed in the plug 32, the opening being reduced in diameter at its lower portion and formed with a beveled seat 35. Above the bottom-plate 14 the outlet plug 32 is provided with four radially-extending ducts 36 communicating with the axial passage 34 whereby the fluid in the reservoir 10 may pass through the radial ducts 36 into the axial aperture 34 and downwardly through the beveled seat 35.

To control the rate of flow of the liquid from the reservoir 10 a needle-valve is provided comprising a rod 37 which is adjustable longitudinally of the opening in the plug 32 by means of a screw engagement with internal threads 38 in the plug. The lower portion of the rod 37 is reduced in diameter to form the needle 41 which is pro-

vided with a pointed lower extremity 42 adapted to fit the beveled seat 35 to tightly close the outlet from the reservoir. An axially bored bushing 44 is threaded into the aperture 30 in the top-plate 13 to provide a bearing for the needle-rod 37. A fluted knob 45 is formed on or secured in any suitable manner to the upper end of the rod 37 to provide a convenient means for adjusting the needle-valve. The bushing 44 is provided with an intermediate annular shoulder 46 against which is seated the apertured end of a detent-member 47. The detent-member 47 is provided with an upwardly extending spring-arm 48 formed at its extremity with a projection 49 adapted to engage the fluted periphery of the knob 45. Above the shoulder 46 the bushing 44 is formed with a threaded extremity 50 upon which is received an interiorly threaded thimble 51. Within the thimble 51 is a suitable packing 52 which is compressed around the rod 37 to form a fluid- and air-tight gland, see Fig. 4. The thimble 51 also serves as the means for securing the detent-member 47 in position and against turning on the bushing 44. It will be understood that the arm 48 is resilient to permit the knob 45 to be manually turned to adjust the needle-valve to vary the size of the outlet at the bottom of the reservoir whereby to control the rate of flow of the lubricant therefrom.

For the purpose of cleaning the lubricant flowing from the reservoir, the plug 32 is enclosed above the bottom-plate 14 with a strainer and filter 53 which may comprise an annularly-shaped strip of felt or any other suitable porous material. The felt strip 53 is held in position surrounding the plug 32 by means of a cylindrical wire screen 54 which encloses it, the screen being soldered or otherwise secured to a ring 56. The ring 56 is held in place by a peripheral shoulder 56 on the outlet plug 32. This construction permits removal of the strainer for cleaning or renewal of the felt by removing the plug.

An annular groove or recess 58 is formed in the under surface of the bottom-plate 14, co-axial with the aperture 31, to accommodate an annular gasket 59 of leather, cork or the equivalent which provides a seat for a small cylinder 61, preferably constructed of glass. The glass cylinder 61 constitutes a transparent wall for an atomizing and measuring chamber, being held in place against the underside of the reservoir 10 by means of a bottom-plate 62 of generally circular shape. A pair of apertured ears 63 project from the rim of the bottom-plate 62, and inserted therethrough are screws 64 threaded into holes in the bottom-plate 14 of the main reservoir. The upper face of the plate 62 is formed with an annular groove 68 in which is positioned a gasket 69 of leather, cork or the like for sealing the joint at the lower edge of the glass cylinder 61.

The purpose of the measuring chamber 61 is to provide for normally atomizing the lubricant and also to segregate a quantity of lubricating fluid from the reservoir 10 to be supplied when the engine is first started. The measured quantity of lubricant is sufficient to permit immediate and easy starting of the engine even though the latter has been idle long enough to cause the customary oil supply in the crank-case to become chilled and the walls of the cylinders and rings to have been drained of the coating of oil essential to their best operation.

A V-shaped or double-branched projection 71 is formed on the bottom of the plate 62, the left-hand arm thereof, as viewed in Figs. 1, 4 and 6,

being provided with a horizontal opening 72 extending therethrough and the right arm with a similar passage 73. A tube 74 has its end secured in the outer orifice of the opening 72 and curves downwardly and upwardly therefrom in a goose-neck formed at its extremity with an annular shoulder 76. An interiorly threaded thimble 77 is carried at the end of the tube 74 engaging the shoulder 76 whereby the tube may be connected with an externally threaded coupling 78. The coupling 78 is internally threaded at 79 and secured to the reservoir 10 by engagement of its external threads with a threaded aperture 81 in the bottom-plate 14. The top-plate 13 is provided with an aperture 82 aligned with the aperture 81 of the bottom-plate 14 and a tube 83 extends downwardly therefrom through the main reservoir. The tube 83 is externally threaded at each end with its lower end screwed into the internally threaded portion 79 of the coupling 78. The upper threaded end 85 of the tube 83 projects above the top-plate 13 to receive a nut or collar 86 screwed down against the top-plate 13.

The uppermost extremity of the tube 83 has a screw-threaded connection with a valve-chamber 100 or housing 88 to be next described. A laterally extending recess 89 is formed in the valve-housing 88 with an externally threaded coupling 90 threaded into its open end, see Fig. 3. An annularly shouldered tube 93 communicating with the axial opening 91 of the coupling 90 is connected to the coupling by means of an interiorly threaded apertured thimble 94. The tube 93 constitutes a suction feed pipe for the apparatus, being connected to the interior of the intake manifold by coupling 92 and hexagonal thimble 95. The valve-housing 88 is formed with a longitudinally extending passage 96 providing communication between the vertical bore 87 thereof and the lateral passage 89. The passage 96 is formed with a tapered seat 97 where it opens into the bore 87 communicating with the tube 83. Projecting from the end of the valve-housing 88 is an internally and externally threaded neck 98 disposed co-axial with the passage 96. Engaging the threaded bore of the neck 98 is a valve-stem 99 formed at its inner end with a reduced extension 100. The extremity of the extension 100 of the stem 99 is formed with a needle point 101 adapted to fit the tapered seat 97 to close the opening into the passage 89.

A fluted knob 102 on the outer extremity of the valve-stem 99 provides means for manually adjusting the valve. A detent-member 103 has an annular portion surrounding the neck 98 of the valve-housing 88 with a resilient arm 104 reaching outwardly alongside the knob 102. The detent-arm 104 is provided at its extremity with a projection 106 adapted to engage the flutes in the periphery of the knob 102. An interiorly threaded thimble 107 is axially bored to accommodate the shank of the valve-stem 99 which extends therethrough. The thimble 107 is screwed onto the neck 98 with a suitable packing 108 in its interior which is compressed around the valve-stem 99 to provide a leak-proof gland for the valve. It will be understood that the spring arm 104 is resilient to permit the knob 102 to be readily turned to cause the needle valve to be advanced or retracted with respect to the tapered seat 97 of the passage 96 whereby to adjust the size of the opening therethrough.

A tube 109, similar to the tube 74, is secured in the orifice of the opening 73 of the right-hand arm of the branched projection 71 on the bottom-

plate 62 of the measuring chamber 61. The opposite flanged end of the tube 109 is held in an interiorly threaded thimble 112 screwed onto a coupling 113 which is threaded through the bottom-plate 14 of the main reservoir 10. Screwed into the threaded bore of the coupling 113 is a vertically extending tube 118 which passes up through the interior of the reservoir and through an opening 122 in its top-plate 13. The 10 upper end of the tube 118 projects above the top-plate 13, and has threaded thereon an axially apertured cap 123. The cap 123 is provided with a plurality of radial air-ducts 124 communicating with the atmosphere. The cap 123 is formed 15 with a circumferential recess 126 in which is soldered or otherwise suitably secured a fine mesh screen 127.

The inner end of the tube 109 secured in the opening 73 of the branched projection 71 communicates with a vertical tube or standpipe 128 held in an opening in the top of the bottom-plate 62 of the atomizing and measuring chamber 61. The upper end of the standpipe 128 opens 20 into the chamber 61 just below the bottom of the main reservoir 10.

From the foregoing description of the apparatus it will be observed that when the device is assembled various conduits are established, one of which, for the lubricant, leads in the following manner: From the interior of the reservoir 10 through the wire strainer 54, felt filter 53 and the radial apertures 36 of the plug 32 downwardly through the axial passage 34 into the atomizing and measuring chamber or small reservoir 61. Another conduit for the lubricant, or for lubricant and air, extends from the atomizing and measuring chamber 61 through the tubes 74 and 83 to the valve-housing 88 and thence to the intake manifold 11 by way of the suction 35 tube 93. An air conduit, opening to the atmosphere through the radial apertures in the cap 123, extends down through the cap and the tubes 118 and 109 to the standpipe 128 opening into the upper portion of the measuring and atomizing chamber 61.

The method of operation of the device is as follows: The filler cap 28 is removed by unscrewing it from the aperture 27 in the top-plate 13 and a supply of lubricant poured into the reservoir 10, after which the cap is replaced.

The needle-valve 37 at the bottom of the reservoir 10 is adjusted to establish the desired rate of flow to the atomizing and measuring chamber 61. By turning the knob 45 the needle point 42 is advanced or retracted with respect to the valve-seat 35 in the plug 32 to regulate the size of the opening through the valve. Satisfactory results have been obtained for motors of conventional size where the adjustment is such as to 55 permit a flow of one drop of oil per minute from the reservoir 10 into the atomizing and measuring chamber 61. When the motor is stopped for but a few minutes, only a small amount of lubricant will be required in its starting, and conversely, when the motor has been idle for a long 60 period of time, as, for instance, overnight, a larger quantity is required. It will be apparent, therefore, that once the valve is properly adjusted the oil will drip continuously from the reservoir 10 into the chamber 61 whereby, when the motor is not running, a quantity of the oil collects in the chamber, which quantity, since it 65 varies in amount in proportion to the time the motor is idle, is always sufficient to start the motor easily when desired.

The oil segregated from the reservoir 10 first fills the chamber 61 and tube 74 to the level of the upper end of the standpipe 128, after which it may flow into the standpipe and tube 109 to the same level. The feed may continue until the chamber 61 is completely filled and the oil attains a level in the tubes 83 and 118, equal to that in the reservoir 10. This condition represents the segregation of a maximum quantity of oil sufficient to start the motor under the most severe atmospheric conditions. It will be evident that the portion of the segregated charge which is in the tubes 83 and 118 is only a small fraction of the whole, consequently satisfactory results are obtained even when the major supply in the reservoir 10 is almost exhausted, and the oil in the tubes and the reservoir 10 is at the level of the bottom of the reservoir.

In starting, as the motor makes its initial revolution, the suction created in the cylinders draws the oil from the chamber 61 upwardly into tubes 74 and 83 and through the valve-housing 88 and tube 93 to the intake manifold 11. After the lubricant is substantially exhausted from the chamber 61 in starting the motor the atomizing tube 118 comes into play as the oil feed is reduced in volume. The tube 118, being opened to the atmosphere through the strainer at the top, serves as a breather pipe, supplying clean air to the chamber 61 by way of the tube 109 and the standpipe 128. The adjustment of the needle-rod 37 in the plug 32, which permits say a flow of one drop of oil per minute when the motor is not running, effects a flow of from two to twelve drops of oil per minute when the motor is functioning due to a partial vacuum being created in the chamber 61 and thus a constant supply of lubricant in the proper amount is furnished to the motor cylinders.

To regulate the amount of oil fed to the cylinders during the normal running of the motor the needle-valve 99 is adjusted by means of the knob 102, this adjustment is best accomplished while the engine is running in accordance with the "sight" feed observed through the glass wall 115 of the chamber 61. A measured flow of oil is thus continuously supplied to the upper portion of the engine to lubricate the pistons, valve-seats and stems. The oil feeding from the chamber 61 during the normal functioning of the motor is 120 atomized by the air sucked in through the breather tube 118 and the lubricant is thus broken up and aerated to form a spray. The oil spray thus introduced into the cylinders has a tendency to break up and dissipate the carbon to 130 prevent its being deposited on the valves and pistons, thus effectually preventing the knocking and clinking caused by pre-ignition. The motor is thus caused to function at maximum capacity over long periods without requiring removal of 135 carbon deposits or regrinding of the valves.

The device thus operates under all conditions to measure in the chamber 61 a charge of lubricant when the motor is idle to be supplied to quickly and easily start the motor; and, further, 140 to furnish a continuous oil spray when the motor is in normal operation whereby the operating elements in the upper cylinders of the engine are constantly lubricated and decarbonized.

The capacity of the atomizing and measuring chamber 61 is determined by the size of the engine or motor to which the device is connected, the motors of passenger cars, for example, requiring a less capacity than truck motors. Measuring chambers of greater or lesser capacity are 145 150

readily provided by removing the screws 64 and substituting a glass cylinder of the desired length, after which the bolts are replaced and tightened to restore the air-tight assembly of the cylinder 61 and the annular gaskets 59 and 69. This operation is conveniently performed without disturbing the connection of the tubes 74 and 109, the flexibility of the tubes permitting sufficient movement of the bottom-plate 62 to permit changing the cylinders.

10 The flow capacity of the drip duct or outlet port 34 of the reservoir 10 is adjusted in accordance with the size of the motor, and normally when once the adjustment has been found satisfactory it is unnecessary to modify it, except for atmospheric changes.

When an internal combustion motor or engine is in continuous operation the walls of the cylinders, pistons, rings and valves are constantly splashed with oil thrown upwardly from the crank-case supply. When the motor is stopped the oil returns by gravity to the crank-case, draining from the upper parts of the motor and leaving the cylinder walls, pistons and valves 25 relatively dry. This condition may evolve to such an extent that the motor is very hard to start, the difficulty being aggravated by the normal tendency of the crank-case oil to congeal when the engine remains idle.

30 Another common difficulty heretofore has been the tendency of the valves and valve-seats to become coated and pitted by carbonaceous products of combustion resulting in an ever-present liability to stick.

35 These problems have been approached in the past by various devices which spray a small quantity of lubricant through the intake manifold and onto the upper portions of the cylinders from a supply independent of the crank-case. Such devices, however, have usually required adjustment or refilling after each starting operation, necessitating frequent attention under the hood of the car; or have been so connected to the source of supply as to be extremely wasteful of the lubricant after the motor is running. The present device when once adjusted operates automatically, requiring no attention on the part of the operator except to maintain a supply of lubricant in the reservoir. My invention therefore provides 45 a most important improvement in the art to which it relates.

While the device is herein illustrated and described as embodied in a preferred form of construction, it is to be understood that various modifications may be made in its structure and arrangement without departing from the spirit or scope of the invention as expressed in the following claims. The device is furthermore susceptible to other applications where it may be advantageously employed and the invention is therefore not limited to a particular use as herein specified. Therefore, without limiting myself in this respect, I claim:

1. In an apparatus for supplying fluid such as 65 lubricant, a reservoir, a measuring chamber, a drip-duct connecting the interior of the reservoir with the measuring chamber, and a feed line leading upwardly from the bottom of the chamber, said measuring chamber being adapted to segregate and store a quantity of fluid fed thereto through the drip-duct in an amount commensurate with the duration of time in which the engine remains idle with no suction in the feed line.

70 2. In an apparatus for supplying fluid such as

lubricant, a reservoir, a measuring chamber beneath the reservoir, a drip-duct leading from the reservoir to the chamber, a feed line leading upwardly from the bottom of the measuring chamber, and a suction line connected to the feed line, said measuring chamber being adapted to segregate and store a quantity of fluid fed thereto from the reservoir in an amount commensurate with the duration of time in which the engine remains idle with the suction line inoperative.

80 3. In an apparatus for supplying fluid such as lubricant, a reservoir, a measuring chamber, a duct connecting the interior of the reservoir with the chamber, a second duct open to the atmosphere and leading into the chamber, and a suction line connected to the chamber.

85 4. In an apparatus for supplying fluids, a reservoir, a measuring and aerating chamber, a duct connecting the interior of the reservoir with the chamber, means for controlling the capacity of the duct to store a quantity of fluid commensurate with the duration of time in which the engine remains idle, an air duct open to the atmosphere and communicating with the top of the chamber, and a suction line leading from the chamber.

90 5. In an apparatus for supplying fluids, a reservoir, a measuring chamber, a duct at the bottom of the reservoir connecting its interior with the chamber, means for controlling the capacity of the duct to feed a measured quantity of fluid into the chamber in an amount commensurate with the duration of time in which the engine remains idle, a feed line at the bottom of the chamber, and a valve for connecting the feed line with a suction line.

100 6. In an apparatus for supplying fluids, a reservoir, a measuring chamber, a duct connecting the interior of the reservoir with the chamber, means to regulate the size of the duct to control the amount of fluid dripped therethrough into the chamber in accordance with the duration of time in which the engine stands idle, an air duct open to the atmosphere and leading into the chamber, a standpipe in the chamber connected to the air duct, and a feed line leading from the chamber.

110 7. In an apparatus for supplying fluids, a reservoir, a chamber, a drip-duct connecting the interior of the reservoir with the chamber, means exterior of the reservoir for controlling the capacity of the drip-duct, a feed line leading from the chamber, and a suction line connected with the feed line.

115 8. In an apparatus for supplying fluids, a reservoir, a measuring chamber, a duct connecting the interior of the reservoir with the chamber, a suction line connected to the chamber, means for controlling the capacity of the first duct, and a valve for controlling the rate of feed through the suction line.

120 9. A lubricating system for internal combustion engines comprising a reservoir, a measuring chamber beneath the reservoir, a duct connecting the interior of the reservoir with the chamber, means for adjusting the capacity of the duct, a feed line for connecting the interior of the chamber with the manifold of the engine, and a valve in the feed line for varying the suction effect of the engine.

125 10. In a lubricating device, a reservoir for a supply of lubricant, a chamber for segregating a portion of the supply, a duct leading from the reservoir to the chamber, means for controlling the feed through the duct, a feed line at the bottom of the chamber for connection with the suc-

- tion line, means to adjust the capacity of the feed line, and an air intake duct opening into the chamber.
11. In a lubricating device, a reservoir for a supply of lubricant, a measuring chamber, a duct leading from the interior of the reservoir to the chamber for drip feeding the lubricant thereto, means for controlling the feed through the duct, and a feed line leading upwardly from the bottom of the chamber for connection with a suction line whereby when no suction occurs in the line a quantity of fluid will drip from the reservoir into the measuring chamber in an amount commensurate with the duration of time in which the motor stands idle.
12. In a lubricating device, a reservoir for a supply of lubricant, a measuring chamber, a duct leading from the interior of the reservoir to the chamber, means in the duct for controlling the feed of the lubricant therethrough, means for connecting the chamber with the intake manifold of a motor, means for regulating the feed from the reservoir to the chamber, and means for regulating the rate of feed from the chamber.
13. In an apparatus for lubricating internal combustion engines, a measuring chamber, a conduit for connecting the chamber with the intake manifold of the engine, a reservoir for a supply of lubricant, a duct at the bottom of the reservoir communicating with the chamber, a valve for controlling the rate of feed through the duct, means exterior of the reservoir for adjusting the valve, and means for adjusting the rate of feed through the conduit.
14. A lubricating system for internal combustion engines including a supply reservoir for lubricant, a measuring chamber, a duct leading from the reservoir to the chamber, means for controlling the capacity of the duct to effect a drip feed of lubricant into the chamber, a feed line for connecting the chamber with the intake manifold of the engine, and an air intake duct leading into the chamber.
15. In a lubricating system for internal combustion engines, a reservoir for a supply of lubricant, a chamber for segregating a measured quantity of lubricant from the reservoir in an amount commensurate with the duration of time during which the engine is idle, a suction line leading from the measuring chamber and adapted to be connected with the engine, and a valve in the suction line for controlling the rate of flow therethrough.
16. In combination, an oil reservoir comprising a transparent cylinder and top- and bottom-plates closing the ends thereof, a measuring chamber on the bottom-plate, a drip valve in the bottom-plate communicating with the measuring chamber, means on the top-plate for adjusting the drip valve, and an air duct communicating with the measuring chamber and open to the atmosphere.
17. In combination, an oil reservoir comprising a glass cylinder and top- and bottom-plates closing the ends thereof, a measuring chamber on the bottom-plate, a drip valve in the bottom-plate communicating with the measuring chamber, means on the top-plate for controlling the drip valve, a feed duct connected with the chamber and leading through the reservoir to the top-plate, a valve on the top-plate for controlling the rate of feed from the measuring chamber, and an air duct leading into the chamber through the reservoir and open thereabove to the atmosphere.
18. In combination, an oil reservoir comprising a glass cylinder, a top closure detachably secured to one end of the cylinder, a bottom closure detachably secured to the opposite end, a measuring chamber detachably secured on the bottom closure member, a drip-duct opening through the bottom-plate into the chamber, an air inlet duct, an oil feed duct, both ducts communicating with the measuring chamber and extending through the top and bottom closures of the reservoir, and a valve on the top closure connected with the oil duct for controlling the feed from the measuring chamber.
19. In combination, an oil reservoir comprising a glass cylinder, a top-plate closing one end of the cylinder, a bottom-plate closing its opposite end, a measuring chamber on the bottom-plate, a drip-duct opening through the bottom-plate into the chamber, a pair of vertical ducts extending through both top- and bottom-plates, one of said ducts open to the air and communicating with the measuring chamber and the other duct leading from the bottom of the measuring chamber, and a valve on the top-plate for controlling the feed through the oil duct.
20. In combination, an oil reservoir comprising a glass cylinder and top- and bottom-plates closing the ends thereof, a measuring chamber on the bottom-plate, a drip valve in the bottom-plate communicating with the chamber, means on the top-plate for controlling the drip valve, an air intake duct connected with the chamber and leading through the reservoir, an oil duct connected with the chamber and leading through the reservoir, and means at the top of the reservoir for controlling the feed through the oil duct.
